UNITED STATES PATENT OFFICE.

SIGMUND HONIG, OF NEW YORK, N. Y.

TELEPHONE RECEIVER.

1,417,479.

specification of Letters Patent. Patented May 23, 1922.

Application filed July 19, 1920. Serial No. 397,437.

To all whom it may concern:

Be it known that I, SIGMUND HONIG, a citizen of the United States, and resident of New York city, in the county of Bronx and State of New York, have invented certain new and useful Improvements in Telephone Receivers, of which the following is a specification.

This invention relates to certain new and useful improvements in loud talking telephone receivers of that type embodying a plurality of diaphragms with multiple connections for conveying sound waves to a single or common ear piece.

15 The primary object of this invention is to provide an improved telephone receiver of the above type which is extremely simple and compact in structure as well as durable and efficient in operation.

20 A further object of the invention is to provide a telephone receiver of the above kind embodying a plurality of horse shoe magnets with improved means for encasing and supporting the same.

25 Another object of the invention is to provide a telephone receiver of the above character embodying horse shoe magnets and pole extensions therefor having vibratable diaphragms at the opposite ends thereof and 30 sound wave conducting means for transmitting the same from both sides of both of the diaphragms to a common ear piece.

A still further object of the invention is to provide a receiver as set forth in the last 35 above mentioned object wherein the distance of travel of the sound waves in all directions from the diaphragms to a point near or in the ear piece will be equal so that said waves will meet or reach said point at the 40 same moment for insuring practicability of the receiver.

Further objects will become apparent as the nature of the invention is better understood, and the same consists in the novel 45 form, combination and arrangement of parts hereinafter more fully described, shown in the accompanying drawing and claimed.

In the drawing, wherein like reference characters indicate corresponding parts 50 throughout the several views,

Figure 1 is an end elevational view of a receiver constructed in accordance with the present invention.

Figure 2 is a substantially central longi-

tudinal sectional view of the casing with the 55 remaining parts shown in elevation,

Figure 3 is a transverse sectional view of the device shown in Figs. 1 and 2 with parts omitted,

Figure 4 is a top plan view of the device 60 shown in Fig. 3 with the casing omitted,

Figure 5 is a perspective view of one of the pole extensions,

Figure 6 is a perspective view of the magnets and pole extensions operatively related, 65

Figure 7 is a perspective view of the tube enclosed by the pole extensions and the tube and ear piece connected thereto, and

Figure 8 is a somewhat diagrammatic view illustrating the means for conducting 70 the sound waves from opposite sides of the diaphragms to a common point adjacent the ear piece.

Referring more in detail to the several views, the present invention embodies a casing including a central ring 5 internally screw threaded at its ends, the threads at one end being left hand threads and those at the other being right hand threads. A pair of end rings 6 are externally threaded and 80 screwed into the ring 5 whereby when the rings 6 are held stationary, and the ring 5 is rotated, the rings 6 will be drawn toward each other or separated according to the direction of rotation of the ring 5. A cap 7 85 is threaded upon the outer end of each ring 6 so as to substantially close the ends of the body formed by the rings 5 and 6.

Three horse shoe magnets 8 are arranged within the casing and fastened together by 90 screws 9 extending through the poles of the magnets, and a pair of pole extensions 10 are fastened to the magnets by these screws 9, said screws extending through openings or apertures 11 provided in the wings 12 which 95 are rigid with the pole extensions 10. The pole extensions are preferably of soft iron and semi-circular in shape as clearly shown in Figs. 3, 5 and 6, and the wings 12 are inserted between the end magnets and the 100 center magnet so that the center or middle magnet is between each pair of wings 12, while the pole extensions 10 are located in the center of the space bounded by the magnets. The extensions 10 do not touch each other, and within the same is inserted a tube 13 of fibre or other non-magnetic material, the tube 13 being slightly shorter than the 105

extensions 10 and being open at both ends. A tube 14 extends through an opening 15 provided in the ring 5 and communicates with the interior of the tube 13 substantially centrally thereof as best seen in Figs. 7 and 8, a suitable ear piece 16 being provided upon the outer end of the tube 14 exteriorly of the casing. As the tube 13 fits snugly between the pole extensions 10, the same is effectively supported in position when the magnets are arranged within the casing as will presently become apparent.

Around each end of the pole extensions outwardly of the magnets, is wound a number of turns of silk covered wire 17 of the same quality and gage as that used in ordinary telephone receivers now in extensive use, and this wire is extended in any suitable manner through the casing and connected to 20 the terminals or binding posts 18 which are carried by the ring 5 opposite the opening 15 and exteriorly of the casing, which terminals are adapted for connection with the telephone wires 19 in the usual manner.

25 At each end of the pole extensions and the wire windings 17 is fastened or soldered a disk 20, the pole extensions extending through central openings provided in the disks 20 as seen in Fig. 2, and these disks 30 are substantially the same as those on the bobbin of an ordinary receiver, but are of such size that they fill the entire width of the case and thus form a chamber between the same and the adjacent diaphragm 21. 35 Each diaphragm 21 is held in position by one of the end caps 7.

The magnets, pole extensions, and associated parts are placed inside of the rings 5 and 6 and fastened by means of a screw 22 40 which is threaded through the ring 5 opposite the opening 15 and which is also threaded into a screw threaded opening 23 provided centrally in the clamp 24 which embraces the central portions of the magnets 8, said clamp 24 having screws 25 for engagement with the magnets so as to rigidly maintain the latter in their proper relation. The tube 14 is then inserted through the hole 15 and connected with the tube 13. The 45 ends of the wire windings 17 are connected with the posts or terminals 18 and the diaphragms 21 are placed in position, after which the covers or caps 7 are screwed on. A pair of curved nipples 26 50 are secured centrally of the covers 7 so that the same interiorly communicate with the casing, and these nipples are connected by means of flexible tubes 27 with the branch nipples 28 provided on the tube 14 adjacent 55 the ear piece 16. When the wires 19 are attached to the posts 18, the device is ready for use.

In operation, the electric current from the telephone wires 19 passes through the wiring 60 17 on the polar extensions and alternately

strengthens and weakens the magnet for causing vibration of the diaphragms 21. These vibrations produce sound waves when the diaphragms vibrate back and forth, and the vibration forward produces sound waves 70 indicated by the arrows *a* in Fig. 8 which pass through the tubes 27 and tube 14 to the ear piece 16. By the backward vibrations, sound waves are produced as indicated by arrows *b* in Fig. 8 which pass through tube 75 13 and tube 14 to the ear piece 16. The routes of travel of the forward sound waves from the diaphragms to the point *c* of Fig. 8 are equal in distance to the routes of travel of the backward sound waves to the point 80 *c* so that both waves will reach the point *c* at the same moment. The sound waves at *c*, therefore, will be the sum of the waves of substantially four receivers so that an extremely loud talking telephone receiver is 85 the result.

It is believed that the construction and operation as well as the advantages of the present invention will be readily understood and appreciated by those skilled in the art. 90

Minor changes may be made therein without departing from the spirit and scope of the invention as claimed.

What is claimed as new is:—

1. In a loud talking telephone receiver, a 95 pair of diaphragms, means for vibrating the same including horse shoe magnets and pole extensions therefor, each end of said extensions being associated with one of said diaphragms, an ear piece, and sound conducting means connected to said ear piece and communicating with opposite sides of both of said diaphragms.

2. A telephone receiver like that set forth in claim 1 wherein the sound conducting means provides a common meeting point for the sound waves the same distance from the opposite sides of both diaphragms.

3. A loud talking telephone receiver including a casing having diaphragms secured in the opposite ends thereof, means for attracting said diaphragms inwardly of the casing including a pair of pole extensions having their ends opposed to said diaphragms, means to lengthen or shorten said casing for moving the diaphragms a greater or lesser distance from the ends of said extensions, a tube within said pole extensions, a sound conducting tube connected with the first named tube and extending exteriorly 110 of the casing, an ear piece upon the outer end of said last named tube, and sound conducting means at the opposite ends of said casing communicating with said second named tube adjacent said ear piece.

4. In a telephone receiver, a plurality of horse shoe magnets, pole extensions secured thereto including wings spacing said magnets, a casing surrounding said magnets, a clamp upon the central portion of said mag- 115 120 125 130

nets, and a screw extending through said casing and engaging said clamp for rigidly supporting the magnets in their operative position within the casing.

5. In a telephone receiver, a plurality of horse shoe magnets, pole extensions secured thereto including wings spacing said magnets, a casing surrounding said magnets, a clamp upon the central portion of said magnets, a screw extending through said casing and engaging said clamp for rigidly supporting the magnets in their operative position within the casing, windings upon said pole extensions, a tube within said extensions open at its ends, diaphragms secured within the ends of the casing adjacent the ends of said pole extensions, an ear piece carrying tube communicating centrally with the first named tube and extending exteriorly of the casing, and means at the outer sides of said diaphragms for conducting sound waves to the ear piece carrying tube exteriorly of the casing.

6. A loud talking telephone receiver including a casing having diaphragms secured in the opposite ends thereof, means for attracting said diaphragms inwardly of the casing including a plurality of pole extensions having their ends opposed to said diaphragms, a tube within said pole extensions, a sound conducting tube connected with the first named tube and extending exteriorly of the casing, an ear piece upon the outer end of said last named tube, and sound conducting means at the opposite ends of said casing communicating with said second named tube adjacent said ear piece.

7. In a telephone receiver, a plurality of horse shoe magnets, pole extensions secured thereto, said pole extensions including opposed substantially semi-circular pole extension members disposed axially of and having their ends projecting beyond the opposite sides of said magnets, and windings upon the projecting ends of said pole extension members.

8. In a telephone receiver, a plurality of horse shoe magnets, pole extensions secured thereto, said pole extensions including opposed substantially semi-circular pole extension members disposed axially of and having their ends projecting beyond the opposite sides of said magnets, windings upon the projecting ends of said pole extension members, and wings projecting laterally from said pole extension members and spacing said magnets.

9. In a telephone receiver, a plurality of horse shoe magnets, pole extensions secured thereto, said pole extensions including opposed substantially semi-circular pole extension members disposed axially of and having their ends projecting beyond the opposite sides of said magnets, windings upon the projecting ends of said pole extension

members, and wings projecting laterally from said pole extension members and spacing said magnets, said wings being fixedly secured to the magnets for supporting the pole extension members spaced from and substantially centrally within the magnets.

10. In a telephone receiver, a plurality of horse shoe magnets, pole extensions secured thereto, said pole extensions including opposed substantially semi-circular pole extension members disposed axially of and projecting beyond the opposite sides of said magnets, wings projecting laterally from said pole extension members and spacing said magnets, said wings being fixedly secured to the magnets for supporting the pole extension members within the magnets, a sound conducting tube held between the pole extension members, and windings upon the opposite ends of the pole extension members at the opposite sides of said magnets.

11. In a telephone receiver, a plurality of horse shoe magnets, pole extensions secured thereto including wings spacing said magnets, a casing surrounding said magnets, windings upon said pole extensions, a tube within said extension open at its ends, diaphragms secured within the ends of the casing adjacent the ends of said pole extension, and an ear piece carrying tube communicating centrally with the first named tube and extending exteriorly of the casing.

12. In a telephone receiver, a plurality of horse shoe magnets, pole extensions secured thereto including wings spacing said magnets, a casing surrounding said magnets, windings upon said pole extensions, a tube within said extension open at its ends, diaphragms secured within the ends of the casing adjacent the ends of said pole extension, an ear piece carrying tube communicating centrally with the first named tube and extending exteriorly of the casing, and means at the outer sides of said diaphragms for conducting sound waves to the ear piece carrying tube exteriorly of the casing.

13. A telephone receiver like that set forth in claim 12 wherein the sound conducting means provides a common meeting point for the sound waves adjacent the ear piece and the same distance from the opposite sides of both diaphragms.

14. In a loud talking telephone receiver, a pair of diaphragms, means for vibrating said diaphragms, and sound-conducting means communicating with opposite sides of both of said diaphragms and providing a common meeting point for the sound waves the same distance from the opposite sides of both diaphragms.

15. A loud talking telephone receiver including a casing having diaphragms secured in the opposite ends thereof, means for attracting said diaphragms inwardly of the casing including a plurality of pole exten-

sions having their ends opposed to said diaphragms, a tube held between said pole extensions, and a sound-conducting tube connected with the first named tube and extending exteriorly of the casing.

16. In a loud talking telephone receiver, a casing including a central ring and end rings adjustably connected for lengthening or shortening said casing, diaphragms at the outer ends of said end rings, caps securing said diaphragms against the outer ends of said end rings, and means within the casing for vibrating said diaphragms attached to said central ring, whereby movement of the end rings relative to the central ring will cause movement of the diaphragms a greater or lesser distance from the diaphragm vibrating means.

17. In a telephone receiver, a plurality of horse-shoe magnets, pole extensions secured thereto and arranged substantially centrally of and axially within said magnets, a casing surrounding said magnets, windings upon said pole extensions, a tube within said extensions open at its ends, diaphragms se-

cured within the ends of the casing in spaced relation to the ends of said pole extensions, disks secured upon the ends of said pole extensions in spaced relation to the diaphragms and contacting the inner surface of the casing so as to provide a chamber between each of said disks and each of the diaphragms, the open ends of the tube each projecting into one of said chambers, and a sound-conducting tube communicating centrally with the first named tube and extending exteriorly of the casing.

18. In a loud talking telephone receiver, a pair of diaphragms, means for vibrating said diaphragms, a single ear piece, and tubular means connected with said ear piece and communicating with opposite sides of both of said diaphragms to provide a common meeting point for the sound waves at said ear piece.

Signed at the city of New York, in the county of New York, and State of New York, this 17th day of July, A. D. 1920.

SIGMUND HONIG.
